TABULATING MECHANISM FOR ACCOUNT-
ING MACHINES

Walter A. Anderson, Bridgeport, Conn., assignor
to Underwood Elliott Fisher Company, New
York, N. Y., a corporation of Delaware

Original application December 29, 1939, Serial No.
311,573. Divided and this application Decem-
ber 10, 1940, Serial No. 369,464

3 Claims. (Cl. 235—62)

This invention relates to accounting ma-
chines, and particularly to a mechanism for
preventing undesirable cycling of the machine
by carriage controlled cycle initiating mecha-
nism while the carriage is tabulating through
one or more columnar positions under the con-
trol of express tabulating mechanism.

This application is a division of my applica-
tion Serial No. 311,573, filed December 29, 1939.

It is customary in bookkeeping operations to
post two or more "debit" and "credit" items in
successive columns between the "old balance"
and "new balance" columns, which are usually
at the left and right extremities, respectively, of
the work forms. Frequently there are no entries
to be made in one or more of the intermediate
columns, so it is unnecessary to stop the carriage
in all these columns. In such instances, it is
desirable to tabulate the carriage from the last
intermediate column in which an entry is post-
ed, directly to a blank cycle column preparatory
to taking the "new balance."

In some instances, one or more of the columns
that are skipped are "automatic cycle" col-
umns—that is, during normal operation of the
machine, the cycle initiating means is automati-
cally operated by mechanism on the carriage
when the carriage moves into these columnar
positions. Therefore, when it is desired to tabu-
late the carriage through these positions it is
necessary that the cycle initiating mechanism
be temporarily disabled so that the machine
will not execute a cycle while the carriage is
moving through these positions. The primary
object of the present invention is to provide
such a disabling mechanism.

With this and incidental objects in view, the
invention consists in certain novel features of
construction and combinations of parts, the es-
sential elements of which are set forth in ap-
pended claims, and a preferred embodiment of
which is hereinafter disclosed with reference to
the drawings which accompany and form part
of the specification.

In the drawings:

Figure 1 is a perspective view of an account-
ing machine of the type to which my improved
tabulating mechanism is adapted.

Figure 2 is a perspective view of the tabulat-
ing mechanism and the various controls there-
for.

Figure 3 is a front plan view of the tabulat-
ing mechanism in normal position.

Figure 4 is a view similar to Figure 3 but
showing the parts in the position to which they

are moved when the customary manual tabulat-
ing key is depressed,

Figure 5 is a view similar to Figure 4 but
showing the parts moved to the position that
they occupy when the "express tabulating key"
is depressed,

Figure 6 is a view similar to Figure 5 but
showing the parts in the position they occupy
when the carriage is about to reach a predeter-
mined position incident to express tabulation
thereof.

Figure 7 is a detail perspective view of a
hinged lug that releases the tabulating mecha-
nism at the end of express tabulation.

Figure 8 is a fragmental right side elevation
showing parts which prevent the carriage from
initiating a machine cycle at improper times,
and

Figure 9 is a detail view of parts of the car-
riage controlled cycle initiating mechanism.

GENERAL DESCRIPTION

This is an improvement on the machine dis-
closed in U. S. Patent No. 2,194,270, issued to
Oscar J. Sundstrand on March 19, 1940.

The machine includes the customary key-
board with "amount keys," "date keys," and "to-
talizer and printer controlling keys." It has the
customary traveling paper carriage that is au-
tomatically tabulated from column to column
and returned from a predetermined point in the
carriage travel. In the present machine, the
power for imparting the leftward or working
stroke to the carriage comprises a spring drum
which is connected to the carriage by a tape,
and the power used in returning the carriage is
derived from the same electric motor that is
used to cycle the machine. These power means,
together with the clutch mechanism and ap-
partenent parts are disclosed in the above men-
tioned patent.

The carriage includes a control plate carry-
ing a series of magazines with control lugs for
automatically controlling the numerous opera-
tions that are controlled manually by the key-
board. The forward ends of these magazines
strike one of a pair of tabulating stops as the
carriage tabulates from right to left, to arrest
the carriage in the various columns. The stops
are arranged to be cooperatively actuated by
either of two separate controls to release the
carriage from one column to the next. One of
these controls is operated as an incident to each
machine cycle to automatically tabulate the car-
riage to the next column, and is also operated

by the customary "tabulating key" on the keyboard, for the same purpose. The other control may be termed an "express tabulating key," which upon depression withdraws the effective tabulating stop from engagement with its abutting magazine. The stop is then held in ineffective position while the carriage passes through the succeeding intermediate columns. When the carriage reaches the blank cycle column, an element carried by the carriage releases the tabulating stop to arrest the carriage in this column.

DETAILED DESCRIPTION

INDEX OF TOPICS

1. The machine sections.
2. Carriage tabulating mechanism.
3. Automatic tabulation of the carriage.
4. Manual tabulation of the carriage.
5. Express tabulation of the carriage to a predetermined column.
6. Carriage controlled starting mechanism.
7. Preventing the machine from cycling during travel of the carriage.

1. The machine sections

Referring to Figure 1, the machine includes the customary keyboard 1 having "amount keys" 2 and operation controlling keys 3 including the customary "manual tabulating key" 4, an "express tabulating key" 5, type bars 6 for printing on the work sheets, and a laterally movable paper carriage 7 mounted on a track 8. A control plate 11 is mounted on the paper carriage and carries a plurality of control magazines 12 for automatically controlling the operations of the machine in predetermined columnar positions. The carriage is provided with the customary roller platen 13 and has a bail structure 14 for facilitating the insertion of front fed forms.

The machine is actuated by an electric motor (not shown). The motor is started by the closing of suitable switch mechanism and is coupled to the main actuating shaft (not shown) by a suitable clutch mechanism upon depression of a "motor bar" 15.

2. Carriage tabulating mechanism

The tabulating mechanism is mounted on a plate 16 (Figures 2 and 3) mounted in the rear of the machine beneath the forward end of control plate 11. Plate 16 is supported for sliding movement in a direction parallel to the travel of the carriage. This sliding movement is made possible through the provision of slots 18 registering with screws 17 mounted in the machine frame. A spring 21 connected to the upper arm of a lever 22 pivoted at 23 tends to move the plate toward the right. The upper arm of the lever carries a stud 24 lying within a recess 25 on plate 16. The lower arm of lever 22 is connected to a dash pot (not shown) of any desired construction. When the carriage is released for tabulation, spring 21 moves the plate to its right hand position wherein the left ends of slots 18 are engaged with screws 17 as shown in Figures 2, 5 and 6.

A lever 26 is mounted for pivotal movement on a stud 27 secured in plate 16. The right end of lever 26 constitutes a tabulating stop 30 coacting with a companion stop 31 formed upon a slide 32 mounted for vertical movement on plate 16 by means of a screw 33 extending through a slot 34 in slide 32, and by a lever 35 pivoted to slide 32 at 39 and fulcrumed on a stud 36 se-

cured to plate 16. A spring 37 normally holds stop 31 in its lower ineffective position shown in Figures 2 and 3. A spring 38 tends to hold stop 30 on lever 26 in its upper position where a lug 46 on lever 26 rests against a stud 45 on lever 35. As before stated, the carriage is provided with a plurality of magazines 12 (one for each position at which it is desired to have the carriage stop) to coact with the tabulating stops 30 and 31. When the carriage is moved to the left by the spring motor, it brings a magazine 12 against tabulating stop 30. The stop 30 is permitted to slide to the left, through the provision of a slot 41, through which stud 27 extends. This tensions spring 38 until the left end of lever 26 strikes an abutment 42.

The spring of the spring motor which pulls the carriage to the left has sufficient strength to hold lever 26 and plate 16 in their left hand positions (Figures 2 and 3) when the carriage is at rest, causing springs 38 and 21 to be normally tensioned.

When the carriage is in its position of rest, one of the magazines 12 rests against the tabulating stop 30. When the carriage is to be released for movement from one column to the next, stop 30 is lowered and stop 31 is simultaneously raised. These stops are so positioned that stop 31 is elevated sufficiently to lie in the path of movement of magazines 12 before stop 30 is lowered out of the path of the magazines (see Figure 4), so that before the carriage is released for tabulation, it moves from its position of contact with stop 30 to a position of contact with stop 31, these stops being slightly offset in the direction of travel of the carriage. After the stops are so moved, and the magazine 12 has moved into engagement with stop 31, plate 32 is lowered to its original position. This movement releases the carriage to the action of the spring motor which effects the desired tabulation. During this tabulation, stop 30 is raised by spring 38 to its normal position as soon as the magazine passes to the left thereof. This places stop 30 in position to engage the next magazine.

3. Automatic tabulation of the carriage

Tabulation of the carriage from one column to another by operation of the stops 30 and 31 may be performed automatically by the general operator of the machine. To accomplish this, the following connections are provided.

A lever 43 (Figure 3) is pivoted on a stud 44, and has its right end forked to engage pin 45 carried by lever 35. The left end of lever 43 (Figure 2) overlies a slide 47 corresponding to slide 685 in the aforementioned patent. As disclosed in this patent, during the first half of a machine cycle slide 47 is raised, and during the second half of the cycle the slide is lowered. During the rise of the slide, stop 30 is lowered as stop 31 is raised, and during the fall of the slide, spring 37 lowers stop 31 to release the carriage for its tabulating movement. As slide 47 is lowered, stud 45 (Figure 3) is raised, allowing spring 38 to move stop 30 into its raised position at the proper time, as explained above.

4. Manual tabulation of the carriage

Mechanism similar to that disclosed in the beforementioned patent, and under control of the customary manual tabulating key, is provided to permit manual operation of the tabulating mechanism. This mechanism includes the customary "tabulating key" 4 (Figures 1 and

2) carried by a lever 48 pivoted on a rod 51 fixed in the machine frame. The rear end of lever 48 carries two lugs 52 and 53. Lug 52 lies under the left arm of lever 43, and lug 53 lies under the left end of a lever 54. Depression of "tabulating key" 4 raises the left arm of lever 43, thereby raising the tabulating stop 31 and lowering the tabulating stop 30. When the operator releases "key" 4, a spring 55 (Figure 2), connected to this key and to the machine frame, restores the key to its normal position. This restoration allows spring 37 to lower stop 31, releasing the carriage as above explained.

Lever 54 is pivoted on stud 27 and is connected with lever 26 by an intermediate lever 56 also pivoted on stud 27. The right arm of lever 56 is connected with lever 26 by a pin-and-slot connection 57, and the left arm of lever 56 has a shoulder 58 engaging the upper end of an arm 60 pivoted at 61 to lever 54. A spring 59 connected between arm 60 and lever 54 normally tensions the arm clockwise about pivot 61, engaging its upper end with shoulder 58. This mechanism provides an alternate connection between the tabulating mechanism and the "key" 4, so that when the left end of lever 43 is moved rearwardly in the machine by depression of the customary "normalizer key" 69 (Figure 1) (the operation of which is fully described in Patent No. 2,194,270), to such an extent that lever 43 no longer lies above lug 52 and slide 47, it will still be possible to tabulate the carriage by depression of "key" 4. It will be noted, however, that in such instances, although lever 26 is lowered from the path of the magazine 12, the tabulating stop 31 is not simultaneously raised as it is when these parts are operated by movement of lever 43. This is due to the fact that the lower arm of lever 26 lies under the pin 45 but does not embrace it as does the right end of lever 43. This makes possible express tabulation of the carriage until the "tabulating key" 4 is released.

5. Express tabulation of the carriage to a predetermined column

As explained above, it is desirable in certain bookkeeping operations to tabulate the carriage from the last intermediate column where an entry is posted, to a predetermined column, without stopping in the intervening columns. The mechanism for accomplishing this is under the control of the "express tabulating key" 5 and comprises a bell crank 62 (Figure 2) pivoted at 63 in the machine frame and having one arm thereof underlying a pin 64 fixed on the stem of "key" 5. The opposite arm of the bell crank is pivoted at 65 to a link 66, the opposite end of which is pivoted at 67 to a depending arm of a bail 68 pivoted on a rod 71 secured in the machine frame. Bail 68 has a forked arm 72 that embraces a pin 73 fixed on one end of a lever 74 pivoted on rod 51 adjacent lever 48. The rear end of lever 74 carries a lug 75 corresponding to lug 53 on lever 48, and likewise underlies the left end of lever 54. By the connections just described, depression of "key" 5 raises lever 54, and through its connection with lever 26, lowers tabulating stop 30 out of the path of magazines 12 to permit express tabulation of the carriage. It will be noted that depression of "key" 5 does not move lever 43, since there is no lug on lever 74 corresponding to lug 52 on lever 48. Therefore, stop 31 remains ineffective during these operations.

A latch 76 (Figure 3) is provided to hold stop

30 out of the path of the magazines 12 until the carriage has reached a predetermined position where the latch is released to permit stop 30 to rise and engage the next magazine. Latch 76 is pivoted on stud 36 and is normally tensioned clockwise about the stud by a spring 81 to a position where the latch bears against a pin 82 fixed in lever 26. A shoulder 83 is provided on latch 76 to engage pin 82 and hold tabulating stop 30 out of the path of magazines 12 (see Figure 5) when lever 26 is actuated by the "express tabulating key" 5.

To restore stop 30 to effective position so it can arrest the carriage at the desired column, lever 26 must be released after the carriage passes the last column it is desired to skip, and before it reaches the column in which it is to stop. To accomplish this, a magazine 12 carrying a lug 84 (Figures 5, 7 and 8) is placed on the carriage in a position immediately to the left of the magazine that is to stop the carriage. The details of mounting lug 84 are shown in Figure 7, and comprise a pin 85 that extends between the side walls of the magazine and on which lug 84 is pivoted. A spring 86, coiled about pin 85 and lying within a slot in the lug, has one end resting on the lug and its opposite end resting on the base of the magazine to normally tension lug 84 downwardly, as shown in Figure 7. Lug 84 projects into the path of the upper end of latch 76 as shown in Figures 5 and 8. Hence, after the carriage tabulates through the columns to be skipped, the lug strikes latch 76, rocking the latch counter-clockwise about stud 36 against the tension of spring 81, and releasing pin 82 from shoulder 83, as shown in Figure 6. Immediately upon such releasing action, lever 26 rises under the tension of spring 38, placing stop 30 in position to stop the carriage at the desired column.

When the carriage returns to the right, after completing its working stroke, lug 84 strikes the upper edge of latch 76, but due to its being pivoted on its magazine 12, merely rises when it strikes the latch, and returns to its lower position when it passes the latch.

The releasable connection between levers 54 and 56 is provided to disconnect "key" 5 from lever 26 as soon as latch 76 becomes effective to hold the lever in depressed position. This prevents the carriage from tabulating past the proper position if the operator should fail to release the "key" as soon as it is fully depressed. This connection operates as follows.

As lever 54 is raised by depression of key 5, the left side of arm 60 strikes a pin 87 (Figure 3) on plate 16. This rotates arm 60 counter-clockwise about pivot 61 against the tension of spring 59, withdrawing the upper end of arm 60 from engagement with shoulder 58, as shown in Figure 5. This occurs immediately after shoulder 83 engages pin 82, so that as soon as lever 26 is latched down, the "key" is rendered ineffective to hold the lever down, should the latch be released before the "key" is restored to its raised position. Upon the release of "key" 5, a spring 88, connected between lever 54 and plate 16, restores the lever, bringing the upper end of arm 60 into the plane of shoulder 58, whereupon spring 59 rocks the arm clockwise about pivot 61 into engagement with the shoulder in readiness for the next operation.

It might be here noted that depression of the customary "tabulating key" 4 during regular bookkeeping operations, where the "normalizer key" is not depressed, will not cause lever 26 to be

latched in its depressed position. As explained above, depression of the "tabulating key" 4 when the "normalizer key" is not depressed rocks lever 43 as well as lever 54, and rocking of lever 43 raises slide 32. In the present disclosure, slot 34 in slide 32 is long enough to permit slide 32 to become effective against the magazines 12 when the slide is raised, but is at the same time short enough to arrest the movement of lever 43, and consequently "key" 4, before the "key" rocks lever 54 far enough to cause lever 26 to be latched down.

6. Carriage controlled starting mechanism

This machine is equipped with a mechanism similar to that disclosed in Patent No. 2,194,270 operated by the carriage, as it moves into a columnar position, to initiate a machine cycle. This mechanism may be termed "carriage controlled motor repeat mechanism," and is operated by control lugs such as 91 (Figures 8 and 9) placed in those magazines 12 occupying columnar positions wherein it is desired to have the machine automatically cycled. As the carriage advances to these columnar positions, the lugs 91 engage a pawl 92 on a selector lever 93 pivoted at 94 in the machine frame. The left end of lever 93 lies above a rod 95 suitably guided for vertical movement and having its lower end resting on the horizontal arm of a bell crank 96 pivoted at 97 in the machine frame. The vertical arm of the bell crank is recessed to receive the lower end of a link 98 that is connected with mechanism for initiating a cycle (link 98 corresponds to link 726 in Patent No. 2,194,270). As lug 91 engages pawl 92, lever 93 is depressed to rock bell crank 96 clockwise and thrust link 98 forward to initiate the cycle.

7. Preventing the machine from cycling during travel of the carriage

It may be that in an express tabulating operation one or more of the intermediate columns that are to be skipped have their magazines 12 equipped with lugs 91 to initiate cycles when the carriage is stopped in these columns. It is therefore necessary to provide a means to prevent these lugs 91 from being effective to start the machine when the carriage passes through these columns. The following mechanism is provided for this purpose.

An extension 101 (Figure 8) formed on bell crank 96 lies in the horizontal plane of a flange 102 formed on a bracket 103 secured to the right end of plate 16 (Figure 2). When a magazine 12 strikes stop 39, and pushes plate 16 toward the left as before described, flange 102 is withdrawn from the path of movement of extension 101, as shown in Figure 3. In such position, bell crank 96 is free to be rocked to initiate the cycle as above described. When, however, stop 39 is lowered out of the path of magazines 12, as it is during express tabulations, spring 21 (Figure 3) moves plate 16 toward the right to the position

shown in Figures 5 and 6, as previously described. Such movement of plate 16 brings flange 102 into the vertical plane of extension 101. The width of the flange (Figure 8) is sufficient to lock bell crank 96 against clockwise movement so that a cycle cannot be started by lugs 91. Pawl 92 is mounted in a frame 104 pivoted at 105 on lever 93. A strong spring 106 connected between frame 104 and lever 93 permits the pawl to yield as lugs 91 engage therewith when flange 102 is in position to lock bell crank 96 against rotation.

While the form of mechanism herein shown and described is admirably adapted to fulfill the objects primarily stated, it is to be understood that it is not intended to confine the invention to the one form of embodiment herein disclosed, for it is susceptible of embodiment in various forms all coming within the scope of the claims which follow.

What is claimed is:

1. In an accounting machine, a traveling carriage movable through working and return strokes, means operated by the carriage for initiating a machine cycle, means for arresting the carriage in columnar positions during its working stroke, a blocking means to prevent operation of the cycle initiating means while the carriage is traveling from one columnar position to another, and means for withdrawing the blocking means from effective position by the movement of the carriage as the carriage is being arrested in a columnar position.

2. In an accounting machine, a traveling carriage movable through working and return

strokes, means operated by the carriage for initiating a machine cycle, means for arresting the carriage in columnar positions during its working stroke, the arresting means including a movable member on the machine frame, the carriage holding the member in one position, means connected with the movable member for blocking movement of the cycle initiating means when the member is in another position, the member moving the blocking means out of effective position when the member is moved by the carriage as the carriage is being arrested by the member.

3. In a machine of the class described, a traveling carriage movable to a plurality of columnar positions, means for initiating a machine cycle, means on the carriage to operate the cycle initiating means, mechanism to tabulate the carriage from one columnar position to another, the mechanism including a member mounted on the machine and moved in one direction by the carriage as the latter moves into a columnar position in which it is to stop, means to move the member in the opposite direction as the carriage moves out of a columnar position, and means operated by the member to render the cycle initiating means ineffective when the member is in the position to which it is moved when operated by the said moving means.

WALTER A. ANDERSON.
